US0D1070888S

(12) **United States Design Patent** (10) Patent No.: **US D1,070,888 S**
(45) Date of Patent: ** Apr. 15, 2025

(54) **DISPLAY SCREEN WITH GRAPHICAL USER INTERFACE**

(71) Applicant: **BRIDGESTONE CORPORATION**,
Tokyo (JP)

(72) Inventors: **Kodai Sato**, Tokyo (JP); **Patrik Bednar**, Bratislava (SK); **Karol Kastella**, Bratislava (SK)

(73) Assignee: **BRIDGESTONE CORPORATION**,
Tokyo (JP)

(**) Term: **15 Years**

(21) Appl. No.: **29/917,807**

(22) Filed: **Nov. 22, 2023**

(30) **Foreign Application Priority Data**

May 30, 2023 (JP) ..... 2023-010945 D

(51) **LOC (15) Cl.** **14-04**

(52) **U.S. Cl.**

USPC **D14/485**

(58) **Field of Classification Search**

USPC D14/485-495

See application file for complete search history.

(57) **CLAIM**

The ornamental design for a display screen with graphical user interface as shown and described.

DESCRIPTION

The sole FIGURE is a front view of a display screen with graphical user interface showing our new design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
